[57] CLAIM

The ornamental design for a racket frame, as shown and described.

DESCRIPTION

FIG. 1 is a front elevational view of a racket frame showing my new design;
FIG. 2 is a side elevational view thereof;
FIG. 3 is a bottom end view thereof; and
FIG. 4 is a top end view thereof.
The rear side is a mirror image of FIG. 1.

FIG. 3

FIG. 4
